UNITED STATES PATENT OFFICE

166,765

WOVEN PLASTIC FABRIC

Vaclav Petracek, Long Island City, N. Y.

Application December 5, 1951, Serial No. 17,614

Term of patent 3½ years

(Cl. D87—3)

To all whom it may concern:

Be it known that I, Vaclav Petracek, a citizen of no country, residing in Long Island City, county of Queens, and State of New York, have invented a new, original, and ornamental Design for a Woven Plastic Fabric, of which the following is a specification, reference being had to the accompanying drawing, forming part thereof, wherein,

The figure on the drawing is a plan view of a piece of woven plastic fabric showing my new design.

I claim:

The ornamental design for a woven plastic fabric, substantially as shown.

VACLAV PETRACEK.
